UNITED STATES PATENT OFFICE.

ANDREW YUROW, OF NEW YORK, N. Y.

LOCK.

1,415,503.

Specification of Letters Patent.

Patented May 9, 1922.

Application filed July 14, 1920. Serial No. 396,134.

To all whom it may concern:

Be it known that I, ANDREW YUROW, a citizen of the United States, residing at New York, county of New York and State of New York, have invented certain new and useful Improvements in Locks, of which the following is a specification.

This invention relates to improvements in door locks, particularly locks comprising a skeleton bolt which is normally pressed inwardly, and it is the object of the invention to provide a lock which may be opened from the inside without a key but requiring the use of a key to open it from the outside.

Another object of the invention is to provide a lock in which the skeleton frame of the bolt is operated by a knob and is kept, if desired, locked in its inoperative position by suitable means provided for this purpose.

Further objects and advantages of the invention will become apparent as the description proceeds, reference being had to the accompanying drawing, and to the appended claims in which the novel features of the invention are more particularly set forth.

In the drawing—

Figure 1, is a front elevation of a casing containing the lock constructed according to the present invention, attached to the inside of a door.

Figure 2 is a top plan view thereof, and Figure 3 is an inner view along line 3—3 of Figure 2, after removal of the rear plate of the casing.

Figures 4 and 5 illustrate in two views partly in section, the contour of the bolts.

As illustrated, the lock comprises a casing 10 of the well known oblong shape which is adapted to be secured to the inner face of a door in any desired manner, for instance as shown by screws 11, the face of the casing in contact with the door being formed by a removable plate, provided with a key-hole 12.

The bolt has the form of an oblong rectangular skeleton member comprising side bars 13 and 14, connected at their forward ends by a cross-bar 15 extended beyond the side bars 13 and 14 as at 16 and 17 and being substantially triangularly shaped in cross-section to form a sharp web adapted to engage with a keeper consisting of an angle plate 18, 19 adapted to be secured by suitable screws or the like to the door frame and

having three rearwardly turned hook members 20, 20' and 20'' adapted to be normally engaged by the bar 15, so that the extensions 16 and 17 of the bar 15 rest against inner shoulders of the members 20 and 20'', while wedge-shaped shoulders 21 and 23 of the casing 10 rest against the outer faces of said members 20 and 20'', and lugs 22 on the outer members 20 and 20'' engage suitable recesses in the shoulders 21 and 23.

The side bars 13 and 14 of the skeleton member are formed with two rearwardly extending bars or rods 24 and 26 provided at their inner ends with small operating plates 27 and 28 respectively. A partition wall 29 is arranged transversely within the casing 10 in approximately the center thereof, and rests against shoulders 30 and 31 formed with the inner walls of the top and bottom plates 32 and 33 of the casing respectively. Coiled springs 34 and 35 are wound around the rods 24 and 26 respectively and their inner ends rest against the plates 27 and 28, while their outer ends rest against the partition wall or plate 29. These springs have the tendency to normally hold the skeleton member in engagement with the hook members of the keeper 18. An operating member 36 provided with two operating fingers 37 and 38 is pivotally secured to the inner wall of the cover plate 25 of the casing 10, which at this place has an opening for the passage of the cylindrical stem of the knob 40, the lower edge 39 of which is hammered down upon the inner face of the member 36, so that the same will be turned about its pivot upon the operation of the knob at either direction in such a manner that one or the other finger of 37 or 38 of the member 36 will engage and press against one or the other of the operating plates 27 or 28 respectively in order to slide the skeleton bolt member out of engagement with the keeper 18 against the action of the springs 34 and 35, so that the door can be opened by the operation or rotation of the knob in one or the other direction from the inside and by a key operating said knob from the outside in order to be automatically locked when the knob or key is released.

A sliding latch 39' is slidable between pairwise arranged guides 40 and 41 transversely to the casing on the inner face of its wall 25, and its rectangularly bent upper arm 42 is provided with a hook 43 at its outer end, adapted to engage a recess within

the bar 13 at the lower edge thereof. Intermediate its ends the latch 39 is provided with a pin 44 extended through an elongated slot in the wall 25 of the casing and carrying an operating slide plate or knob 45 at its outer end sliding over a suitable flange on said front wall surrounding the slot therein. It will be clear, that upon the operation of the knob 45 to engage the hook 43 with the bar 13, the skeleton member of the bolt will be locked against operation by the knob 40, and the door will be kept closed, so that it may also not be opened from the outside by a key. When however the knob 45 is operated to disengage the hook 43 from the bar 13, it will be possible to open the door from the outside by a key as well as from the inside by the operation of the knob in either direction which both will produce an engagement of either finger 37 and 38 of plate 36 with either of the plates 27 and 28, as the case may be, to press the skeleton member of the bolt against the action of the springs 34 and 35 to the outside and out of engagement with the hooks 20, 20' and 20" of the keeper 18, so that the door may now be opened.

It is believed the operation of my improved lock will be apparent from the foregoing description, and it will be clear that changes may be made in the minor details and arrangements of the parts without departing from the scope and spirit of my invention as set forth in the appended claims.

Having thus described my invention what I claim as new and desire to secure by Letters Patent of the United States is—

1. A lock comprising a casing, a bolt 40 therein composed of a pair of side bars, a cross-bar uniting said side bars at their front ends, projections on said cross bar adapted to normally engage a keeper, said keeper composed of three members, two of said 45 members provided with shoulders for the engagement by said projections of the cross-bar, shoulders on said casing engaging the outer faces of the outer keeper members, one of the side bars of said bolt being recessed at its lower edge, means for operating said 50 bolt, a sliding latch sliding between guides on the inner face of the casing wall, a rec-

tangular bent arm on said latch provided with a hook at its outer end adapted to be engaged in the recess of said side bar, a pin 55 on said latch extending through a longitudinal slot in the front wall of the casing to play therein, a slide plate on the outer end of said pin, and a socket surrounding said slot upon which said slide plate is gliding for locking and unlocking said bolt and its operating means.

2. A lock of the character described comprising a casing, a partition wall, transversely arranged in said casing, a skeleton 65 bolt therein composed of a pair of side bars, operating plates at the inner ends of said bars, springs surrounding said bars between said partition wall and said operating plates, a cross-bar uniting said side bars at their 70 front ends, projections on said cross bar adapted to normally engage the keeper, said keeper composed of three members, a central and two outer keeper members, one of said members provided with shoulders for 75 the engagement by said projections of the cross bars, shoulders on said casing engaging the outer faces of the outer keeper members, one of the side bars of said bolt recessed at its lower edge, an operating member 80 pivotally secured to the inner wall of the cover for said casing, an outer operating knob having a cylindrical stem extending into the casing and having its lower edge hammered down upon the inner face of said member and a pair of operating fingers on 85 said member adapted to engage the operating plates at the ends of the bolt bars, for operating said bolt upon the operation of said knob, a sliding latch sliding between 90 guides on the inner face of the casing wall, a rectangular bent arm on said latch provided with a hook at its outer end adapted to be engaged in the recess of said side bar, a pin 95 on said latch extending through a longitudinal slot in the front wall of the casing to play therein, a slide plate on the outer end of said pin, and a slide socket surrounding said slot upon which said slide plate is gliding for locking and unlocking said bolt 100 and its operating means.

In testimony whereof I have affixed my signature.

ANDREW YUROW.
